FILING CABINET SHELL

Frank D. Jonas, East Williston, N. Y., assignor to Oxford Filing Supply Co., Brooklyn, N. Y., a partnership composed of Richard A. Jonas, Richard A. Jonas, Jr., Robert P. Jonas, Frank D. Jonas, and Edward F. Jonas

Application March 31, 1934, Serial No. 718,447

2 Claims. (Cl. 45—2)

This invention relates to improvements in shells or containers for sliding drawers.

An important object of this invention is to provide such a shell constructed of cardboard, fibre and similar semi-durable material, in such a manner that it will be rugged and strong and capable of withstanding the abuses and wear to which such shells are subjected to when employed as cases for drawers in which papers and the like are filed.

A further object of this invention is to provide an open mouth shell or container having reinforced edges constructed so that the shells may be stacked one on the other and interlocked in vertical alignment.

A still further object is to employ a reinforcing construction such that adjacent stacks of these shells may be interlocked so that they are transversely held against movement and substantially interlocked into a unit.

These and many other objects as will appear from the following disclosure are secured by means of this invention.

This invention resides substantially in the combination, construction, arrangement and relative location of parts all as will be described in greater detail in the following specification in connection with the attached drawings and pointed out in the appended claims.

In the drawings,

Figure 1 is a plan view of a shell blank of one form of the invention;

Fig. 2 is a cross sectional view taken on the line 2—2 of Figure 1;

Figs. 3 and 4 are plan and end views of one of the interlocking clips;

Fig. 5 is a detail view of the manner in which these clips are employed to interconnect a pair of stacked shells;

Fig. 6 is a view of the bolt and nut by means of which adjacent stacks may be locked together;

Fig. 7 is a front elevational view of two stacks of shells showing the manner of interlocking one shell on the other and of interconnecting and locking adjacent stacks;

Fig. 8 is a perspective view of a casing assembled from the blank of Fig. 1; and

Fig. 9 is a vertical longitudinal-sectional view taken on the line 9—9 of Fig. 8.

At the present time there is a growing demand for inexpensive transfer files in which correspondence and the like, which is infrequently referred to, may be stored so as to be readily accessible. This type of file is at present being

constructed in many forms of corrugated cardboard, fibre and similar materials. The files consist of individual shells or containers which are open at the front, formed up from single piece blanks of such materials. The present invention is directed to several forms of such structures in which provision is made for reinforcing the relatively weak containers. It is common practice to stack these containers one on the other into columns of as much as six to ten feet high. When the drawers which are used with such stack shells are full, it is apparent that the vertical loads on these relatively, flexible, shells are considerable, especially in view of the fact that they are open at the front. The purpose of this invention is to provide a reinforcing structure for the open ends of the shell, which, in addition to reinforcing the open ends, provide vertical columns which carry portions of the load to the floor, and which, at the same time, interlock the stack shells into a more rigid and unitary structure than would be the case if they were simply set one on the other. Further, in accordance with this invention these reinforcing means are constructed so that adjacent stack shells may be interlocked to form them into a structural unit and to strengthen them against transverse strains and hold them against transverse movement. The manner in which these objects are accomplished will now be apparent by detail reference to the drawings.

A suitable shell blank in accordance with this invention is illustrated in Figure 1. The dotted lines in this figure with the exception of the one at the member 12, and the curved dotted line of the member 16, represent the lines of fold which divide the blank into the portions which are the top, bottom, sides and end of the shell. Thus the blank comprises the top portion 1, the side portions 2 and 3, the end portions 4, 5, 6, 7 and 8 and the bottom portion 9 and additional reinforcing side portions 10 and 11. The upper end of the portion 1 is reinforced by some form of inherently rigid member such as a U-shaped strip of metal 12 which fits over the free end edge of the portion 1 and is secured thereto in any suitable manner, as for example, by rivets as indicated in the figure. Likewise, the free edge of the bottom portion 10 is reinforced as for example by means of a gummed fabric tape 13, which likewise is formed over the edge as a channel member. The free end edges of the side portions 2 and 3 are provided with structural reinforcing members which may be of metal, wood, fibre and the like. As illustrated in Fig-

ure 1, these reinforcing members comprise a portion 14 which lies on the inner surface of the sides 2 and 3 and extends into as shown in Figure 2, a rectangular column formation 15. On 5 the faces of the sides 2 and 3 are the washers 16 opposite to the flange portion 14. These reinforcing members are clamped to the edges of the sides by the rivets 17 as is clear in Figure 2. Thus the free end edges of the sides 2 and 3 have 10 firmly secured thereto, hollow reinforcing members which act as vertical load bearing columns as will appear later.

The shell is formed from this blank as follows: The portions 10 and 11 are folded up out 15 of the plane of the figure to a position at right angles to the bottom 9 along the dotted lines. Likewise, the portions 2 and 3 are similarly folded up at right angles to the portion 1. The portions 1, 2 and 3 are then swung over by bending 20 along the dotted lines which define the rear portion 8 after the flaps 4 and 5 have been folded in at angles to the portions 2 and 3. This operation brings the portion 1 into parallel relation above the portion 9 and brings the portions 2 and 25 3 down into parallel and contacting relation with the portions 10 and 11 which fit inside thereof. This gives a rectangular container open at the front having double thickness side walls. The flaps 4 and 5 lie parallel to the portion 8 as 30 indicated in Figure 7 to provide a double thickness herein. When the additional strength is desired, the flaps 4 and 5 may be sufficiently long to provide the extensions 6 and 7 which may be folded over parallel thereto to provide double 35 thickness flaps which with the rear end piece 8, provide a triple thickness at the back of the container.

The relative width of the portions 2, 3, 4, 5, 6, 40 7, 10 and 11 are such as will be apparent to those skilled in the art by allowing for the thickness of the material so that when the shell is completely formed, vertical loads on the shell will be carried by all of these portions. Thus the width of these portions in the figure represents 45 the height of the shell when folded and allowing for the thickness of the material the effective height of all of these parts will be the same so that they will all cooperate in absorbing their share of the vertical loads on the shell.

50 It is for this reason that the flaps 4 and 6 may be folded over to give a double thickness thereby adding greater strength to the rear end of the shell for vertical loads. With the shell thus formed, as will be apparent from Figure 7, an exceedingly strong container results having steel or the like reinforcement on the sides and top of the open edge of the shell and the gummed type reinforcement on the lower edge of the open end. The notches 18 provide spaces for the 55 bosses 14'. The formation of the end of the portion 8, adjacent the portion 9, is merely for the purpose of accommodating the overlapping folds of the material which is relatively thick. This feature will likewise be apparent to those skilled in the art. As shown in Figure 1, the ends of the flange 14 are provided with bosses 14' adjacent the reinforcing strip 12 to in effect increase the transverse extension of these flanges in the direction of their thickness. Thus, when the sides 2 60 and 3 are folded up at right angles to the portion 1, these bosses 14' will engage the reinforcing

member 12, insuring proper positioning of the sides at right angles to the top and further imparting strength to the shell transversely thereof.

In stacking these shells one on the other, the 5 clips shown in Figs. 3, 4 and 5 are employed to interconnect the reinforcing columns 15 thereby 10 aligning the shells and interlocking them. These 15 clips consist of rectangular channel members 18 with a press at their center to form a projecting boss 19. The opposite ends of the channel have U-shaped portions struck out to form spring 10 tongues 20 which are provided with raised bosses 21 on their ends. The bosses 19 contact adjacent 15 ends of the member 15 to carry the vertical loads directly to the floor.

15 As is clear from Figures 5 and 7, the columns 15 near each end are provided with perforations which receive the bosses 21 when the clips are inserted between adjacent ends of the columns 15 of a pair of stacked shells. The manner in 20 which these clips interconnect the columns is clear, particularly from Figure 5. As illustrated in Figure 7, adjacent columns may be interlocked by means of the bolts and wing nuts in Figure 6. The bosses 19 on the clips provide recesses in 25 which the wings of the wing nut 23 may seat. The head of the screw 22, and the washer thereon, rest on the front of these bosses as is clear in Figure 7. When the bolts are screwed up tight, the adjacent columns are locked together. 30 This reinforces the stacks so as to prevent side sway whereby the stacks are held in true vertical relation, adapting them to better stand vertical loads.

35 From the above description it will be apparent that the principles of this invention may be embodied in numerous physical forms by those skilled in the art without departure from the scope thereof. I do not, therefore, desire to be strictly limited to the disclosure as given for 40 purposes of illustration, but rather to the scope of the appended claims.

What I seek to secure by United States Letters Patent is:

1. A combination comprising a plurality of 45 open end filing cabinet shells arranged in at least two columns of adjacent stacks, each shell being made of flexible, fibrous material, and having a reinforcing metal column of hollow section secured to the sides of the open ends thereof, means 50 for interlocking adjacent shells comprising a metal key lying in the adjacent ends of the columns and having a central peripheral boss to space the columns and means interconnecting the adjacent keys at the bosses of adjacent 55 stacks to lock the stacks together.

2. A combination comprising a plurality of open end filing cabinet shells arranged in at least two columns of adjacent stacks, each shell being made of flexible, fibrous material, and having a 60 reinforcing metal column of hollow section secured to the sides of the open ends thereof, means for interlocking adjacent shells comprising a metal key lying in the adjacent ends of the columns and having a central peripheral boss to 65 space the columns, means interconnecting the adjacent keys at the bosses of adjacent stacks comprising a bolt and wing nut having the ears of the wing nut in the bosses of adjacent keys to lock the adjacent stacks together.

70 FRANK D. JONAS.
